UNITED STATES PATENT OFFICE.

MANUEL SALINAS PEREZ, OF ALBUQUERQUE, NEW MEXICO.

POWER-TRANSMITTING APPARATUS.

1,248,392.

Specification of Letters Patent. Patented Nov. 27, 1917.

Application filed September 25, 1917. Serial No. 193,165.

To all whom it may concern:

Be it known that I, MANUEL SALINAS PEREZ, a subject of the Mexican Republic, residing at Albuquerque, in the county of 5 Ber-nalillo and State of New Mexico, have invented certain new and useful Improvements in Power-Transmitting Apparatus; and I do hereby declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

This invention relates to new and useful improvements in power transmitting apparatus, and comprises an apparatus having various details of construction and combinations of parts as will be hereinafter fully described and then specifically defined in the appended claims.

I illustrate my invention in the accompanying drawings, which, with the letters 25 of reference marked thereon, form a part of this application, and in which,

Figure 1 is a side elevation of the apparatus,

Fig. 2 is a top plan view, and

Fig. 3 is an enlarged detail view of a detail of the invention.

Reference now being had to the details of the drawings by letter A designates a balancing receptacle which may be of any size 35 or shape, preferably oblong and having concaved ends B, and which is balanced upon a shaft C, which is suitably journaled in bearing members D, integral with the base E. Said receptacle A has a closed top A' with 40 a filling opening therein closed by means of a cap F, and an exit H in its bottom, the said receptacle being adapted to contain any suitable liquid, such as water I. At each end of the top of the receptacle are the contracted 45 projections L, each having a slot therein for the reception of the rods N, which are pivoted at their lower ends on the pins O upon the base E. A coiled spring M is mounted on each rod and bears between the 50 base E and the under surface of a projection L, the office of said springs being to take up jar as the balancing receptacle tilts.

Bars Q are fastened one to each side wall 55 of the receptacle, near the ends of the latter, and to the lower end of each bar is pivoted the outer end of the handle P, which is in

the nature of a wrench (see Fig. 3), and which handles each has serrated links pivoted to one another. The end link of each series, carries a pin P', designed to be engaged by a hook J at the end of the bar J', which latter is fastened rigidly to the handle P. It will be noted upon reference to Fig. 2 of the drawings, that there are two of said handle wrenches, one on either side of 60 the receptacle, and each is arranged to grip the shaft when the handle is swung in one direction. Said shaft is designed to be rotated in one direction only, being prevented from a reverse direction by means of the 65 pawl R which engages the teeth of a ratchet wheel R'.

A power wheel T is mounted on a shaft T' supported in the standard T'', and has a series of buckets T³ radiating from its circumference which are adapted to catch water from the nozzle T⁴ through which water under pressure from any suitable source may be directed. Rotating with the wheel is a gear S which is in mesh with a pinion S' 75 journalled on a stub shaft S² upon the standard T'', and S³ is an arm fixed to the pinion S' and said arm is pivoted to the end of the link Y, which in turn is pivoted to the long arm of the lever X. Said lever X is 80 pivoted on a pin X', carried by the standard X² upon the base. A short link X³ pivotally connects the end of the short arm of the lever X, with a pin Z on a lug Z' at 85 one end of the receptacle.

In order to illustrate the work that may be accomplished by my invention, I have illustrated a pulley G upon the shaft and about which a rope G' is adapted to be wound, a weight G² being fastened to the 90 latter, the rope passing over a pulley G³.

In operation, the water wheel is rotated by the weight and the impact of the water coming against the pockets on the circumference of the wheel, and through the pivotal link and lever connections with the receptacle, the latter is first caused to tilt upon the shaft, in one direction, causing the water therein to rush toward one end of the receptacle, the coil springs M taking up jar 105 and vibrations. As the shaft is designed to rotate in but one direction, the teeth on the links of the handle wrench will turn idly, when the receptacle tilts in one direction, but when the receptacle tilts in the opposite 110 direction, or the direction of the rotation of the shaft, the teeth of the links of the chain

will grip the shaft and impart a rotary movement thereto.

By varying the amount of the contents of the tilting receptacle the amount of power applied by the apparatus may be regulated.

While I have shown and described specifically a mechanical construction of apparatus whereby my power transmitting mechanism, may be accomplished, it will be understood that I may vary the details of the apparatus without departing from the spirit of the invention.

It will be at once evident that the effectiveness of the apparatus may be regulated by varying the amount of water or other liquid contained in the receptacle.

Having thus described my invention what I claim to be new is,

1. A power transmitting apparatus, comprising a tilting receptacle adapted to contain a liquid, a shaft upon which the receptacle is mounted, handles having pivotal connection with the receptacle on either side of the shaft, serrated gripping links connected to each handle and adapted to grip said shaft to cause same to rotate in one direction only, and means for tilting said receptacle, as set forth.

2. A power transmitting apparatus, comprising a tilting receptacle adapted to contain a liquid, a shaft upon which the

receptacle is balanced, bars secured to the receptacle, one on either side of the shaft, a handle pivoted to each bar, a series of serrated links connected to said handles and designed to grip said shaft to cause same to rotate in one direction, means for preventing a reverse rotary movement to the shaft, and means for taking up jar incident to the tilting of the receptacle, as set forth. 40

3. A power transmitting apparatus, comprising a tilting receptacle, having a curved bottom and adapted to contain a liquid, a shaft upon which the receptacle tilts, handles having pivotal connection with the receptacle, and oppositely disposed, a series of serrated links connected to each handle and designed to grip the shaft to cause same to rotate in one direction only, a ratchet and pawl to prevent a reverse rotary movement 50 to the shaft, springs to take up jar incident to the tilting of the receptacle and, a power wheel, having pivotal link and lever connections with one end of said receptacle, as set forth. 55

In testimony whereof I hereunto affix my signature in presence of two witnesses.

MANUEL SALINAS PEREZ.
